UNITED STATES PATENT OFFICE.

FRANK S. HYATT, OF NEW YORK, N. Y.

DESIGN FOR A CAP FOR POWDER-CONTAINERS.

No. 39,590.

Specification for Design.

Patented Sept. 29, 1908.

Application filed July 3, 1908. Serial No. 441,921. Term of patent 7 years.

To all whom it may concern:

Be it known that I, FRANK S. HYATT, a citizen of the United States, residing at New York city, borough of Brooklyn, in the county of Kings and State of New York, have invented a new, original, and ornamental Design for Caps for Powder-Containers, of which the following is a specification, reference being had to the accompanying drawings, forming part thereof, in which—

Figure 1 is a side elevation of a cap showing my new design. Fig. 2 is a plan of the same.

I claim:

The ornamental design for a cap for powder containers as shown.

FRANK S. HYATT.
